[57] CLAIM

The ornamental design for an electronic language translator, as shown and described.

DESCRIPTION

FIG. 1 is a perspective view of an electronic language translator showing my new design;

FIG. 2 is a side elevational view thereof;

FIG. 3 is a side elevational view thereof opposite that shown in FIG. 2;

FIG. 4 is an end elevational view thereof, the opposite end elevational view being a mirror image;

FIG. 5 is a top plan view thereof; and,

FIG. 6 is a bottom plan view thereof.

FIGS. 2-6 are shown on an enlarged scale.

FIG. 1.

FIG. 5.

FIG. 6.
